KNITTING MACHINE

Aaron S. Staff, New York, N. Y., assignor to
Texagon Mills Inc., Ridgefield, N. J., a corpora-
tion of New Jersey

Application August 12, 1948, Serial No. 43,862

5 Claims. (Cl. 66—86)

1

This invention relates to warp knitting machines, which include one or more rows of needles and a plurality of thread guide bars, which are swung transversely of the rows of needles and also shogged during the knitting operation. More particularly, the invention is concerned with a novel warp knitting machine, in which, although a large number of thread guide bars are employed, the bars are so mounted that the arc, through which they travel in passing from one side of the needles to the other, is no greater than that traversed by a much smaller number of bars in a machine of conventional construction. The new machine can, accordingly, be operated at a higher output rate than prior machines having the same number of guide bars.

In warp knitting machines as now constructed, it is customary to support the thread guide bars on brackets depending from a shaft extending lengthwise of a row of needles and mounted above them for axial rocking movement. The thread guide bars are mounted to depend from rods extending lengthwise of the row of needles and supported for endwise movement in the several brackets. The thread guides carried by each bar lie in a row and, although the guides in the several rows are mounted to converge, the eye ends of guides in respective rows are spaced apart, so that, if a considerable number of rows of guides are used, the distance across the rows from one outer row to the other is substantial. In the lapping of the threads about the needles, the arc, through which the shaft is swung to pass the guides from one side of the row of needles to the other, depends on the distance across the rows, and, as that distance is increased with an increase in the number of guide bars used, the duration of the knitting cycle is correspondingly increased and the output of the machine reduced. Also, the number of guide bars that can be used in a conventional machine is limited, because, if too great a number of bars are used, the inlay threads are liable to be caught by the needles with resultant defects in the fabric.

The present invention is directed to the provision of a novel warp knitting machine, in which a large number of thread guide bars may be employed without reducing the speed of the machine below that of a machine of usual construction having a much smaller number of guide bars and without encountering difficulties because of the inlay threads being caught by the needles. In the new machine, a number of guide bars are mounted for endwise movement in aligned slots in blocks carried by a rock shaft and the bars are

2

so supported that their eyes are substantially in alignment. The number of guide bars mounted in the blocks may vary in accordance with the requirements of the construction of the fabric to be made, but, since the free end of the guides carried by the bars in the blocks are aligned, the use of more than one bar in the blocks does not require an increase in the arc, through which the rock shaft is swung, and, therefore, does not prolong the knitting cycle or cut down the output rate of the machine.

In addition to the novel features mentioned, the invention includes a thread guide bar of novel construction, which can be produced and maintained in working condition easily and at low cost.

For a better understanding of the invention, reference may be had to the accompanying drawings, in which:

20. Fig. 1 is a vertical sectional view on the line 1—1 of Fig. 2 of a knitting machine embodying the invention;
21. Fig. 2 is a fragmentary sectional view on the line 2—2 of Fig. 1;
22. Fig. 3 is a view in side elevation of a thread guide bar used in the machine;
23. Fig. 4 is a sectional view on the line 4—4 of Fig. 3; and
24. Fig. 5 is a view in end elevation of a part of the machine.

The knitting machine illustrated in the drawings includes end frames 10, between which extends a shaft 11 mounted in the frames for rocking movement. The shaft is rocked by an arm 12 fast thereon and is connected to a rod 13, which is reciprocated endwise by cam means (not shown). A plurality of hangers 14 are attached to the underside of shaft 11 in spaced relation and, at its lower end, each hanger carries a cross-arm 15, on which are mounted slotted plates 16, 17, and 18. Each plate is seated in a channel in one face of the cross-arm and held in place by a screw 19 passing through its slots and into the cross-arm; the plate thus being adjustable vertically. Plates 16 and 17 have openings in their lower ends and rods 20, 21, extending lengthwise of the machine and reciprocable endwise, pass through aligned openings in plates 16, 17, respectively. An angle iron 22 extends the length of rod 20 and its horizontal flange is connected rigidly thereto by arms 23. A plurality of thread guide assemblies 24 are mounted on the downwardly extending flange of angle iron 22, each assembly including a row of thread guide needles 25, the eyes of which lie in alignment. An angle

iron 26 is rigidly attached by arms 27 to rod 21 and its downwardly extending flange carries thread guide assemblies 27a having thread guides 28 arranged in a row with their eyes in alignment. In the machine illustrated, the threads handled by guides 25 are for knitting purposes and those handled by guides 28 are inlaid in the fabric.

An angle iron 29 is attached by its vertical flange to the plates 18 and a plurality of blocks 30 are mounted on the horizontal flange of the angle iron at intervals along the machine. Each block 30 is formed of metal and it is generally of arcuate shape and formed with a plurality of slots 31 opening through its lower curved wall 32. The slots converge toward wall 32 and, at their inner ends, the slots have cylindrical enlargements 33.

A plurality of thread guide bars in the form of thin metal strips 34 are mounted in corresponding slots in the blocks 30 along the machine and each strip has beads 35 of cylindrical form attached to its upper edge in spaced relation. The strip and the beads thereon are of such dimensions that the strip can be passed endwise through corresponding slots in blocks 30 and, when in operative position, a bead on the strip lies within the cylindrical enlargement 33 at the inner end of the slot in each block.

Each of the strips 34 carries thread guide needles 36 in distributed arrangement thereon. Each such needle is made of a thin strip of metal, which has a wide face secured by brazing to one face of the strip 34 and, just below the lower edge of strip 34, the needle is bent at 36a through 90°, so that the free ends of the needles disposed along the strip 34 thus have their flat faces parallel. The eyes 37 in the needles 36 on all the strips 34 lie substantially in alignment. There are ten slots in each block 30 in the machine illustrated and thus there are ten strips 34. The thread guide needles 36 on successive strips across a block 30 are offset lengthwise of the strips. Thus, in a series of ten guide needles 36 along the machine, the first needle is mounted on strip 34 at one side of each block 30 and the next guide needle along the machine is mounted on the next strip 34 mounted in the blocks. This arrangement repeats itself lengthwise of the machine.

A restoring spring 38 is connected to one end of each strip 34 and also to a fixed part of the machine. The other end of each strip is attached to a rod 39, which is reciprocated endwise by the patterning mechanism to shog the strip. The rods 20 and 21 are also provided with shogging means and restoring spring means, as is customary.

The machine includes a row of latch needles 40 lying below the lower ends of the thread guides 25, 28, 36 and carried in assemblies 41 attached to a needle bar 42, which is raised and lowered during the operation of the machine.

With the construction described, there are ten sets of thread guides 36 carried on respective strips 34, which are independently movable for shogging purposes, but, since the ends of all the thread guides 36 are in alignment, the shogging movement of each strip 34 is somewhat limited. In the machine shown, there are four latch needles 40 between successive thread guides 36 along the machine, so that each strip 34 can be shogged only through the space of four latch needles without interference of its thread guides with those on the adjacent strip. However if

the adjacent strip is shogged at the same time, the first strip may have a shogging movement greater than four needles.

The thread guides 36 are employed for inlay threads, and, since these guides all have their eyes substantially in alignment, the distance transverse to the row of latch needles from the ends of guides 25 to the ends of guides 36 is no greater than the corresponding distance in an ordinary machine having only three thread guide bars. Accordingly, although there are twelve thread guide bars in the new machine, the arc, through which rock shaft 11 must move to lay the threads about the needles is no greater than that required in a conventional machine with three thread guide bars. The duration of the knitting cycle in the new machine is thus the same as that in an ordinary machine having three thread guide bars. Also, because of the close spacing of guide needles 36 to guide needles 25, no difficulty is encountered because of threads manipulated thereby becoming caught by the latch needles.

The thread guide strips 34, having the guide needles 36 attached to them in the manner described, can be easily produced and maintained in working condition. Such a thread guide bar assembly is much simpler than those heretofore employed, in which the ends of guide needles are embedded in lead or a plastic material and the assemblies attached in a row to a bar.

In the machine illustrated, ten thread guide bars or strips 34 are used and the thread guides 36 on each such bar are separated a distance equivalent to forty latch needles. It will be understood that the number of thread guide bars and the spacing of the thread guides thereon depends upon the fabric to be produced and, for some purposes, a less number of thread guide bars 34 may be employed or the thread guides may be differently spaced on the bars. While it is possible, by using blocks 30 with more than ten slots to make use of more than ten bars 34, ten such bars are sufficient for practically all purposes.

I claim:

1. In a knitting machine having a row of needles, the combination of a shaft extending lengthwise of the row and mounted for axial rocking movement, a rod mounted on the shaft for endwise movement lengthwise of the row of needles, a guide bar attached to the rod, a plurality of thread guides carried by the bar, a plurality of blocks mounted in spaced relation along the shaft, each block having a plurality of slots convergent toward the needles, a plurality of strips extending lengthwise of the row of needles, each strip being mounted for endwise movement in corresponding slots in the several blocks, and a plurality of thread guides mounted in spaced relation along each strip, the guide eyes of the guides on the strips all lying substantially in alignment.

2. In a knitting machine having a row of needles, the combination of a shaft extending lengthwise of the row and mounted for axial rocking movement, a rod mounted on the shaft for endwise movement lengthwise of the row of needles, a guide bar attached to the rod, a plurality of thread guides carried by the bar, a plurality of blocks mounted in spaced relation along the shaft, each block having a plurality of slots convergent toward the needles, a plurality of strips extending lengthwise of the row of needles, each strip being mounted for endwise movement

in corresponding slots in the several blocks, and a plurality of thread guides mounted in spaced relation along each strip, the guides on successive strips across the blocks being successively offset lengthwise of the strips and the guide eyes of the guides on the strips all lying substantially in alignment.

3. In a knitting machine having a row of needles, the combination of a shaft extending lengthwise of the row and mounted for axial rocking movement, a plurality of brackets mounted in spaced relation along the shaft and extending toward the needles, a rod carried by the several brackets for endwise movement, a guide bar attached to the rod, a plurality of thread guides mounted on the guide bar, a plurality of blocks carried by the brackets in spaced relation lengthwise of the row of needles, each block having a plurality of slots convergent toward the needles, a plurality of strips extending lengthwise of the row of needles, each strip being mounted for endwise movement in corresponding slots in the several blocks, and a plurality of thread guides mounted in spaced relation along each strip, the guide eyes of the guides on the strips all lying substantially in alignment.

4. A thread guide assembly for use in a knitting machine which comprises a plurality of blocks, each having a plurality of convergent slots, the slots converging toward corresponding faces of the several blocks, a plurality of strips,

each mounted for endwise movement in corresponding slots in the several blocks, and a plurality of thread guides mounted in distributed relation along each strip, the guide eyes of the guides on all the strips all lying substantially in alignment.

5. In a thread guide assembly, the combination of an elongated thread guide bar having a flat face and a plurality of thread guides carried by the bar, each guide being formed of a narrow metal strip having one wide face at one end thereof in contact with and secured to the flat face of the bar, the strip being bent between its ends through 90° about its longitudinal axis, the free ends of the guides lying parallel and having guide eyes lying substantially in alignment.

each mounted for endwise movement in corresponding slots in the several blocks, and a plurality of thread guides mounted in distributed relation along each strip, the guide eyes of the guides on all the strips all lying substantially in alignment.

5. In a thread guide assembly, the combination of an elongated thread guide bar having a flat face and a plurality of thread guides carried by the bar, each guide being formed of a narrow metal strip having one wide face at one end thereof in contact with and secured to the flat face of the bar, the strip being bent between its ends through 90° about its longitudinal axis, the free ends of the guides lying parallel and having guide eyes lying substantially in alignment.
